UNITED STATES PATENT OFFICE.

AUGUSTUS P. STEVENS, OF BROOKLYN, NEW YORK.

CARPET-CLEANING MACHINE.

SPECIFICATION forming part of Letters Patent No. 251,806, dated January 3, 1882.

Application filed November 14, 1881. (No model.)

To all whom it may concern:

Be it known that I, AUGUSTUS P. STEVENS, of Brooklyn, Kingscounty, New York, have invented Improvements in the Construction of Carpet-Cleaning Machines; and I do hereby declare that the following is a full, clear, and correct description of the same, reference being had to the accompanying drawings, making part of this specification, and to the letters of reference marked thereon, in which—

Figure 1 is a side elevation of my invention. Fig. 2 is a top view of the same. Fig. 3 is an end view of the same. Fig. 4 is a detached view of the beaters and the means of operating them.

In the drawings like parts of the invention are pointed out by the same letters of reference.

The nature of the present invention consists in improvements in the construction of carpet-cleaning machines, as more fully hereinafter set forth, and will be found to relate more particularly to the construction of the beaters and the means to operate them, and to the means employed to collect (so to speak) the dust beaten from the carpet and to dispose of the same, the object of the invention being the production of a machine for cleaning carpets thoroughly and with the least possible wear to the carpet cleaned.

To enable those skilled in the arts to make and use my invention, I will describe its construction and operation.

A is a frame-work, made preferably of wood, and formed by bolting together the sections composing it, for supporting the operative parts of the machine.

B are boxes secured upon the cross-braces C of the frame-work, within which are received the ends of the rotating reciprocating shafts D, upon which are attached the beaters E, usually formed from cane, rattan, or other suitable material. These beaters E are curved and held upon the shafts D, and are placed a short distance from each other. Within the outer beaters, E, are placed the smaller beaters E². When placed in the frame A the shafts D are so positioned that the beaters E and E² upon one of the shafts D shall be above one shaft, while the beaters E and E² shall be below the other shaft.

F shows a rock-shaft, the journals of which are passed through openings in the frame A, and which is placed about centrally in the upper part of this frame. This shaft is provided with beaters G and G², similar in construction to the beaters E and E². 55

H and H² are pulleys secured upon the ends of the shafts D, and I is a pulley secured upon one end of the shaft F. Over the pulley I is passed a belt, J, the ends of which are secured upon the pulleys H and H²; and K are belts the ends of which are attached to the pulleys H and H² and the quadrantal plate L, hung upon a stud secured in one of the cross-braces C, about midway between the pulleys H and H². 60 To the center of this quadrantal plate L is pivoted one end of a pitman, M, the opposite end of which is fastened to a crank-arm, N, secured upon a revolving shaft, O, having its bearing in the boxes P, supported by the auxiliary frame-work A².

Upon each side of the rock-shaft F, and having their bearings in the frame-work A, are the spiral-shaped brushes Q, upon the ends of which are secured the pulleys R, and upon the opposite end of one the pulley S. 75

At the bottom of the frame-work A, having their bearings in the boxes T, are the revolving shafts U, upon one of which the carpet to be cleaned is wound, and upon the other of which the carpet is wound after it has been passed through the machine and been submitted to the action of the beaters. These shafts U may be driven, as in the present instance, by a system of gearing, V, W, and X, or by a series of belts; but as they form no essential feature of the present invention, being only intended to receive and allow the carpet to be properly presented to the action of the beaters and spiral brushes, acting indirectly, I do not consider it necessary to describe their construction in detail. They are, however, prevented from working too rapidly, and governed, as to the extent to which they will allow the carpet to be passed through the machine, by the side brakes, Y, which straddle them, are pivoted at one end to the frame A, and have a spiral spring, Q², attached at one end to the under side of the brake, its opposite end being attached to the base supporting the frame-work A. 95

The frame-work A is provided with a series of bands or belts, *a*, extending from the upper cross-brace to the lower cross-brace, the object of which is to form a "backing," so to speak, for the carpet, that it may receive the full force of the blows imparted to it by the beaters E and E².

Over the pulley S upon one of the brushes Q, and a pulley, 3, upon a shaft, 4, in the auxiliary frame-work A², is passed a belt, 5, and over the pulleys 6 and 7 the belt 8 is passed, and thus motion is given to the brushes Q, which are intended to be driven at a very high rate of speed.

Such being the construction, the operation will be readily understood: The carpet to be cleaned is attached at one end to one of the shafts U, upon which it is wound, and its opposite end is attached to the other shaft U, upon which, after it is passed through the machine, it is wound. The carpet is slowly unwound from one of these shafts, is passed through the machine upon the inside of the cords or strings *a*, and over the rollers 9, in line with the rotating reciprocating shafts D, and in its passage through the machine is beaten upon its under side by the beaters E E², held upon the rotating reciprocating shafts D, and the beaters G G², secured upon the shaft F.

It will be seen that the beaters are operated by the quadrantal plate L, being connected to it, as described heretofore, and that this quadrantal plate L in turn derives its movement, through the pitman M and crank N, from the shaft O, driven by hand or otherwise. As the carpet passes through the machine and is beaten by the beaters the spiral brushes Q, placed upon the opposite side of the carpet and running at a high rate of speed, suck up the dust, lint, or other matter beaten from the carpet, which is carried off to the chimney or flue over the machine.

In the use of the invention two points of special interest will be noted: First, the carpet is beaten on the back or warp, and, second, the brushes Q are not brought to bear upon the face of the carpet, thus wearing the same, but move rapidly over it and suck up the dust more thoroughly than if brought in contact with the carpet.

The carpet cleaned as described is less liable to be injured or destroyed than in machines as usually constructed.

Having now set forth my invention, what I claim as new is—

1. In a carpet-cleaning machine, the combination, with suitable means for passing the carpet through the machine, of the shafts D, carrying the beaters E and E², the shaft F, provided with the beaters G and G², and a quadrantal plate, L, connected to the shafts D and F, as shown, and operated by the pitman M, crank N, and driving-shaft O, when the same shall be constructed and operate substantially as and for the purposes set forth.

2. In a carpet-cleaning machine, the combination, with suitable means for passing the carpet through the machine, of the spiral brushes Q and the shafts D, carrying the beaters E and E², and the shaft F, provided with the beaters G and G², and a quadrantal plate, L, connected to the shafts D and F, as shown, and operated by a pitman, M, crank N, and driving-shaft O, when the same shall be constructed and operate substantially as and for the purposes set forth.

AUGUSTUS P. STEVENS.
